(57) **CLAIM**

The ornamental design for a cushioned support base for a tablet computer, as shown and described.

DESCRIPTION

FIG. 1 is a top, front and right side perspective view of a cushioned support base for a tablet computer showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top, front and right side perspective view thereof, shown in condition of use with a tablet computer supported on the front face disclosed in broken lines to illustrate an environment; and,

FIG. 9 is a top, rear and left side perspective view thereof, shown in condition of use with a tablet computer supported on the rear face.

The broken lines showing a tablet computer in FIGS. 8-9 represent environmental structure and form no part of the claimed design.

1 Claim, 9 Drawing Sheets
